ROLLING RULE

William E. Evans, Waterbury, Conn., assignor to
 The Waterbury Lock and Specialty Company,
 Milford, Conn., a corporation of Connecticut

Application February 16, 1939, Serial No. 256,695

4 Claims. (Cl. 33—138)

This invention relates to an improvement in rolling rules in which the rule or tape measure is formed from a strip of metal of the concavo-convex type.

5 One object of the invention being to provide a spring tension for the rule as it is being wound into the case or drawn outward therefrom.

Another object of the invention is to utilize 10 that it can not be extended lengthwise.

Other objects are obtained by the novel construction, combination and arrangement of parts 15 as hereinafter described and shown.

In the drawings:

15 Fig. 1 is a front view of the rolling rule construction in accordance with my invention, and showing the outer end of the rule partly withdrawn;

Fig. 2 is an edge view of the same;

20 Fig. 3 is a plan view on an enlarged scale with one side of the case removed and showing the rule partially drawn outward;

Fig. 4 is a similar view showing the rule as 25 partially entered into the case;

Fig. 5 is a perspective view of one part of the case detached; and

Fig. 6 is a perspective view of the end of the rule detached.

30 In carrying out my invention, I employ a case formed from two shells 10 and 11 connected together by a centrally-arranged tubular post 12. The case is provided with an entrance slot 13 and one wall of the slot is turned inward forming a guide lip 14. The case is also formed with 35 inwardly-projecting lugs 15, more or less in number for the purpose as will hereinafter appear. Within the case is a helical spring 16, and this spring corresponds substantially in diameter to the space between the inner faces of the case. The inner ends 17 and 18 of the spring are anchored to the case on opposite sides of the slot 13 and the lugs 15 project between adjacent 40 convolutions of the spring so as to prevent the spring from creeping.

The rule 19 is preferably concavo-convex and is folded at its inner end to provide a loop 20, the overlapping end 21 being secured to the rule by an eyelet 22. Beyond the eyelet, the rule is 50 given a sharp bend or shoulder 23 to engage with and deflect the convolutions of the spring but without increasing the length of the spring. The outer end of the rule is provided with the usual finger-piece 24. The guide lip 14 not only 55 guides the tape into the case but also acts to

prevent the finger-piece 24 from entering the case.

In returning the rule into the case, the shoulder 23 engages the first convolution of the spring and is guided by the lip 14, and engages successive convolutions of the spring so as to press the convolutions outward toward the wall of the case. As the tape enters, each convolution is laid over in position by contact from the convolution preceding it, so as to be in position when 10 the tape arrives, insuring extreme smoothness. The loop of the rule freely turns on the post 12. The rule is, therefore, under equal tension until it has completely entered into the case and obviously is under the same tension until it is 15 fully withdrawn from the case. The spring gives substantially-continuous contact with the rule, and consequently provides for smoother action in drawing out or pushing in the rule. It is 20 obvious without further illustration that instead of using the continuous spring it might be divided into two parts with both ends of each part anchored to the case.

The invention may be carried out in other 25 specific ways than that herein set forth without departing from the spirit and essential characteristics of the invention, and the present embodiment is, therefore, to be considered in all respects as illustrative and not restrictive, and 30 all changes coming within the meaning and equivalency range of the appended claims are intended to be embraced therein.

I claim:

1. A tape measuring device comprising: a case 35 formed with an entrance slot; helical spring means anchored adjacent opposite edges of said slot and extending around within the case; and a flexible rule constructed and arranged to extend through said slot and to be movable endwise in through said slot; said helical spring means 40 being so supported within said case and having its convolutions of such size and said helical spring means and said flexible rule being so constructed and arranged that when said flexible rule is forced endwise in through said slot, the 45 convolutions of said helical spring means are laid over toward the peripheral wall of the case, with said convolutions individually rotating about points of the convolutions located at the outer periphery of said spring means, and in consequence causing said flexible rule to become arranged in a coil within the case.

2. A tape measuring device comprising: a case 50 formed with an entrance slot; helical spring means anchored adjacent opposite edges of said 55

slot and at a number of intermediate locations and extending around within the case; and a flexible rule constructed and arranged to extend through said slot and to be movable endwise in through said slot; said helical spring means being so supported within said case and having its convolutions of such size and said helical spring means and said flexible rule being so constructed and arranged that when said flexible rule is forced endwise in through said slot, the convolutions of said helical spring means are laid over toward the peripheral wall of the case, with said convolutions individually rotating about points of the convolutions located at the outer periphery of said spring means, and in consequence causing said flexible rule to become arranged in a coil within the case.

3. A tape measuring device comprising: a case formed with an entrance slot; helical spring means anchored adjacent opposite edges of said slot and extending around within the case; a centrally-arranged post in said case; and a flexible rule attached to said post and constructed and arranged to extend through said slot and to be movable endwise in through said slot; said helical spring means being so supported within said case and having its convolutions of such size and said helical spring means and said flexible rule being so constructed and arranged that when said flexible rule is forced endwise in

through said slot, the convolutions of said helical spring means are laid over toward the peripheral wall of the case, with said convolutions individually rotating about points of the convolutions located at the outer periphery of said spring means, and in consequence causing said flexible rule to become arranged in a coil within the case. 5

4. A tape measuring device comprising: a case formed with an entrance slot; helical spring means anchored adjacent opposite edges of said slot and extending around within the case; a centrally-arranged post in said case; and a flexible rule attached to said post and formed with an abrupt bend a short distance from said post and constructed and arranged to extend through said slot and to be movable endwise in through said slot; said helical spring means being so supported within said case and having its convolutions of such size and said helical spring means and said flexible rule being so constructed 10 and arranged that when said flexible rule is forced endwise in through said slot, the convolutions of said helical spring means are laid over toward the peripheral wall of the case, with said convolutions individually rotating about points of the convolutions located at the outer periphery of said spring means, and in consequence causing said flexible rule to become arranged 15 in a coil within the case.

WILLIAM E. EVANS. 30
